UNITED STATES PATENT OFFICE.

CHARLES W. LENT, OF CARBONDALE, ILLINOIS.

KROUT-PRESS.

1,153,323.

Specification of Letters Patent. Patented Sept. 14, 1915.

Application filed May 4, 1914. Serial No. 836,365.

To all whom it may concern:

Be it known that I, CHARLES W. LENT, a citizen of the United States, residing at Carbondale, in the county of Jackson, State 5 of Illinois, have invented certain new and useful Improvements in Krout-Presses; and I do hereby declare the following to be a full, clear, and exact description of the invention, such as will enable others skilled 10 in the art to which it appertains to make and use the same.

This invention relates to presses and has special reference adapted for use in the preparation of krout.

15 The principal object of the invention is to provide a novel and improved form of device of this description which is intended to be used in connection with an ordinary barrel or which may be used with a special 20 barrel or receptacle, the device being of such character that varying degrees of pressure can be obtained for different heights of the contents of the barrel without the use of a pressure screw or the like.

25 With the above and other objects in view the invention consists in general of certain novel details of construction and combination of parts hereinafter fully described, illustrated in the accompanying drawings, 30 and specifically claimed.

In the accompanying drawings, like characters of reference indicate like parts in the several views, and:—

Figure 1 is a vertical section through a 35 barrel showing the press applied thereto. Fig. 2 is a top plan view of a barrel with the press applied thereto. Fig. 3 is a partial detail section taken horizontally just below the center of the cross bar, the view 40 looking upward. Fig. 4 is a detail view of one end of the cross bar showing the adjusting means therefor.

In carrying out the objects of this invention as herein illustrated there is disclosed 45 a barrel 10. Mounted within this barrel is a presser head 11, reinforcing strips 13 extending across said presser head. Pivotally connected to these reinforcing strips is a rod 14, preferably rectangular in cross 50 section, and provided on one side with a series of notches 15.

At 16 is a cross bar or lever provided with a handle portion 17 and on this cross bar or lever is a strap 18 through which the vertical member passes. Moreover to the underside of the cross bar is secured a plate 55

19 which is adapted to engage in the notches of the vertical member so that when the lever is tilted slightly the strap engages the back of the vertical member while the plate 60 is held securely in a respective notch.

To one end of this cross bar is loosely pivoted a link 20 which is loosely pivoted as at 21 by its lower end to the barrel 10. A second link 22 is provided adjacent the 65 other end of the lever and this second link 22 has provided in one edge a series of diagonal notches 23 which are adapted to engage a pin 24 carried adjacent the upper part of the barrel diametrically opposite the 70 connection of the first mentioned link.

In operation the krout is placed in the barrel in the usual manner and the plunger head dropped therein after the rod or stem has been fitted through the U-shaped member 75 on the bar. When the plunger head has come to rest on the top of the krout the cross bar is raised until the plate on the under side thereof engages in one of the notches. The cross bar is then pulled down 80 and one of the notches on the link adjacent the handle portion engaged with its pin. From time to time, as the krout compresses, the position of the vertical member and cross bar may be changed. 85

When it is desired to withdraw any of the krout the parts may be released and the plunger head simply turned up, the pivotal connection with the vertical member permitting this motion so that more krout can 90 be placed in the barrel or krout can be withdrawn therefrom.

There has thus been provided a simple and efficient device of the kind described and of the character specified. 95

It will be obvious that many minor changes may be made in the form and construction of this invention without departing from the material principles thereof. It is not therefore desired to confine the invention to the exact form herein shown and described, but it is desired to include all such as come properly within the scope claimed. 100

Having thus described the invention, what 105 is claimed as new, is:—

1. The combination with a receptacle, of a plunger mounted within said receptacle, a stem connected to said plunger and having a series of notches in one side, a cross bar 110 constituting a lever and provided with a strap through which said stem passes, a lip

on the under side of said cross bar adapted to engage in a selected notch upon twisting the lever, a link pivotally connecting one end of the cross bar with the receptacle, and 5 a second link connected to said cross bar adjacent the opposite end and adapted to engage the receptacle.

2. An attachment for barrels comprising a cross plunger, a stem centrally pivotally connected to the cross plunger and having 10 a series of notches on one side thereof, a cross bar provided with a strap where-through said stem passes, a lip carried by

said cross bar and adapted to engage a notch in the stem as the cross bar is forced down, 15 a link having pivotal connection with the cross bar and adapted for connection to a barrel, and a second link having pivotal connection with said bar and adapted to engage a barrel. 20

In testimony whereof, I affix my signature, in the presence of two witnesses.

CHARLES W. LENT.
